Primary Examiner — David Muller*Assistant Examiner* — Nathan Johnston*(74) Attorney, Agent, or Firm* — Eversheds Sutherland (US) LLP(57) **CLAIM**

The ornamental design for a shower bottle holder, as shown and described.

DESCRIPTION

FIG. 1 is a perspective view of a shower bottle holder showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof;

FIG. 9 is a cross-sectional bottom plan view thereof; and,

FIG. 10 is a perspective view thereof.

The broken lines in the figures illustrate the portions of the design that form no part of the claimed design.

1 Claim, 6 Drawing Sheets(56)
